UNITED STATES PATENT OFFICE.

FRANK G. SHUMAN, OF CHICAGO, ILLINOIS.

TAPE HOLDER AND MOISTENER.

1,016,966.

Specification of Letters Patent. Patented Feb. 13, 1912.

Application filed February 13, 1911. Serial No. 608,282.

To all whom it may concern:

Be it known that I, FRANK G. SHUMAN, a citizen of the United States, residing at Chicago, in the county of Cook and State 5 of Illinois, have invented a new and useful Tape Holder and Moistener, of which the following is a specification.

This invention has relation to tape holders and moisteners and consists in the novel construction and arrangement of its parts as hereinafter described and claimed.

The object of the invention is to provide a holder and moistener of simple structure the holder being adapted to retain a roll of 15 tape in such manner that the tape is not permitted to unroll freely from the said roll but by reason of the configuration of the holder and the position of the roll therein sufficient tension is pressed and must be overcome before the tape may be unrolled from the roll. In combination with the holder a moistener is provided across which the tape is drawn as it is unwound from the roll and as it is the intention to use the present invention 20 in combination with tape provided with a gummed surface the gummed surface of the said tape is brought into contact with the moistener and is dampened. Upon the moistener is provided a cutting means for 25 severing the tape into sections as it is unwound from the roll and drawn across the moistener.

In the accompanying drawings:—Figure 1 is a perspective view of the holder and 30 moistener. Fig. 2 is a plan view of the blank from which the holder is made. Fig. 3 is a transverse sectional view of the moistener. Fig. 4 is a plan view of the blank from which the moistener is formed.

The blank from which the body portion of 35 the holder is formed is illustrated in Fig. 2 and consists of a back portion 1 connected with side portions 2 which are in turn connected with front portions or flaps 3. When 40 the body is formed the portions 2 are bent up at right angles to the back portion 1 and the portions 3 are bent at right angles to the portions 2. The portions 2 are in synclinal relation to each other but are disconnected from each other save through the back portion 1. The back portion 1 is provided with suitable perforations 4 through which screws or other supporting devices may be passed. The edges of the portions 45 3 at the opposite sides of the back portion 1 are spaced from each other so that there is

a channel leading from the upper to the lower end of the back portion 1 between the side portions 2 and the front portions 3. The body thus formed is adapted to receive 50 a roll of tape the said roll resting against the inner inclined surfaces of the side portions 2 as indicated in dotted lines in Fig. 1 of the drawings. By reason of the fact that the portions 2 are in synclinal relation the roll is held at its opposite side portions as 55 between the members of a wedge shaped vise or clamp and thus the roll is prevented from permitting the tape to unwind too freely therefrom. In fact the tape must be 60 drawn in an upward direction to unroll the same from the roll for the reason that the roll must be lifted or partially lifted out of contact with the synclinal surfaces of the side portions 2 of the holder.

The blank from which the moistener is formed is illustrated in plan in Fig. 4. This blank consists of a back or body portion 5 having side portions 6 with a bottom portion 7 and an outer side portion 8. The upper 65 end of the outer side portion 8 is continued into a flange 9 which is inwardly turned when the body is formed as illustrated in Fig. 3 of the drawing. A flap 10 is bent back from the upper edge portion of the 70 body portion 5 and is in spaced relation to the said portion 5 of the blank. When the moistener is formed the side portions 6 are 75 bent at right angles to the back portion 5 and the bottom portion 7 is also bent at right 80 angles to the back portion 5 while the other side portion 8 is bent at a right angle to the bottom portion 7. The portion 9 is inwardly bent as above described and the portion 8 is bent in substantial parallel relation 85 to the back portion 5. The edges of the portions 7 and 8 are secured by solder or other means to the edges of the side portions 6 and the upper ends of the side portions 6 project 90 slightly beyond the upper ends of the back 95 portions 5 and the outside portion 8. The projecting ends of the side portions 6 serve as guides between which the tape may be passed. A block of felt 11 is inserted in the moistener and the upper end portions of the 100 said block of felt project slightly above the upper edges of the portions 5 and 8 of the 105 blank of which the moistener is formed. The flange portion 9 will hold the block 11 away from a cutting blade which is applied to the moistener and which will now be explained. The cutting blade 12 is soldered,

riveted, or otherwise secured to the upper edge part and at the outer side of the portion 8 of the blank of which the moistener is formed, and said blade 12 is provided with 5 a serrated cutting edge 13 which is outwardly disposed. As above stated the flange 9 of the blank of which the moistener is formed will hold the upper portion of the block of felt away from the cutting edge of 10 the blade 12 at the same time the tape may be drawn across the upper portion of the block 11 and then brought down against the serrated cutting edge 13 of the blade whereby by the said tape may be readily severed into 15 sections. It is of course understood that the block of felt 11 is saturated with water and as the tape is drawn across the same the gummed surface thereof is moistened and the parts are severed into sections as indicated. 20

Having described the invention what I claim as new and desire to secure by Letters Patent is:—

1. In combination with a holder having 25 synclinal side portions, a moistener formed from a blank of sheet material having a back portion a flap portion substantially parallel with the back portion, side portions with ends which project above the back portion, a bottom portion and a front portion 30

the bottom portion and front portion being secured at their edges to the side portion and a cutting blade mounted upon the upper part of the front portion of the said moistener. 3t

2. In combination with a holder provided with synclinal sides, a moistener adapted to be applied to one of the sides of the said holder and consisting of the blank of sheet material formed with a back portion and a 40 flap adapted to receive between them the edge portion of one of the sides of the holder said moistener also having side portions with ends which project above the back portion, a bottom portion and a front portion the edges of the bottom and front portion being secured to the edges of the said side portion the front portion being provided with an inwardly disposed flange, and absorbent material contained within the 45 moistener and a cutting blade applied to the front portion of the moistener. 50

In testimony that I claim the foregoing as my own, I have hereto affixed my signature in the presence of two witnesses.

FRANK G. SHUMAN.
